UNITED STATES PATENT OFFICE.

FREDERICK HOCHBRUNN, OF NEW YORK, N. Y.

BREECH-LOADING FIREARM.

SPECIFICATION forming part of Letters Patent No. 660,437, dated October 23, 1900.

Application filed February 23, 1900. Serial No. 6,275. (No model.)

To all whom it may concern:

Be it known that I, FREDERICK HOCHBRUNN, a citizen of the United States, and a resident of the city of New York, borough of Manhattan, in the county and State of New York, have invented a new and Improved Breech-Loading Firearm, of which the following is a full, clear, and exact description.

One purpose of the invention is to provide a controlling-ring or cut-off for magazine-rifles adapted to revolve around the bolt and to be carried thereby, the ring being of such construction that it may be quickly turned by the fingers to such position that the cartridges in the magazine will not be acted upon when the extractor is brought into action, thus enabling the arm while the magazine is filled to be used as a single-loader or whereby the ring may be brought to such a position that it will act upon both the extractor and the cartridges in the magazine, enabling the gun to be used as a simple repeater.

A further purpose of the invention is to so construct the ring with relation to the bolt and the extractor that the ring will be carried to such a position that it will be out of engagement with the extractor and also the cartridges in the magazine, enabling the bolt to be withdrawn and the magazine replenished without withdrawing a cartridge that may be in the barrel.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a horizontal section through the breech portion of the barrel of a firearm, the bolt having been carried rearward to expose the magazine and the ring being in such a position that it will not cause a withdrawal of the cartridges from the barrel. Fig. 2 is a plan view of the breech portion of the firearm, the ring being in such position that the arm may be used as a repeater. Fig. 3 is a transverse section through the breech portion of the arm, illustrating the position of the ring when the extractor and cartridges are not to

be engaged. Fig. 4 is a transverse section taken on the line 4-4 of Fig. 2, illustrating the manner in which the ring engages with the cartridges and the extractor. Fig. 5 is a transverse section through the breech portion of the firearm, showing the ring or cut-off in the position it occupies when the firearm is to be used as a single-loader. Fig. 6 is a perspective view of the ring. Fig. 7 is a sectional view of the head of the bolt, illustrating the controlling-ring or cut-off in position thereon. Fig. 8 is a vertical section through the breech portion of a firearm, taken practically on the line 8-8 of Fig. 11, illustrating the bolt in the act of forcing a cartridge in the barrel. Fig. 9 is a transverse section on the line 9-9 of Fig. 8. Fig. 10 is a perspective view of the receiver or frame for the bolt. Fig. 11 is a transverse section on the line 11-11 of Fig. 8, and Fig. 12 is a perspective view of the extractor.

One of the objects of the invention is to provide a controlling-ring or cut-off of such construction that it dispenses with a separate gate for the magazine, while retaining the advantages of a gate, allowing the magazine to be replenished under any conditions, and permitting the gun to be operated as a simple repeater with all the advantages of the Mauser or Lee systems or as a single-shot rifle with magazine held in reserve, as in the Krag-Jorgensen system with a gate.

A represents a portion of the frame of a firearm; B, the bolt; B', the bolt casing or receiver; C, the barrel, to which the bolt-casing is attached; D, a cartridge in the breech of the barrel, and E represents the extractor provided with a recess 10 in its inner face, as shown particularly in Fig. 1.

F represents the improved controlling-ring or cut-off. This controlling-ring or cut-off F is shown in detail in Fig. 6, and its position on the head of the bolt is fully illustrated in Fig. 7. The body 11 of the controlling-ring or cut-off F is circular, or it may be semicircular, and it may be continuous and in ring-like form, as shown in Fig. 6, or it may be in the form of a split ring, and the body is provided with an offset 12 at one side adapted to enter the slot 10 in the extractor E, so that when the controlling-ring or cut-off device is in position on the bolt and the offset 11 is in en-

gagement with the extractor when the bolt is operated the extractor will be also operated. In the further construction of the body 11 of the controlling-ring or cut-off device a thumb or finger piece 13 is formed exteriorly thereon adjacent to the offset 12, which is likewise exteriorly located, and usually the construction of the controlling-ring or cut-off is completed by the addition of a tongue 14 to the body at a point diametrically opposite the thumb or finger piece 13. This finger-piece extends forward from the bottom portion of the ring-body, as is shown in Figs. 6 and 7, and is adapted to engage with the uppermost cartridge in the magazine A' for the purpose of forcing said cartridge into the barrel after the empty shell has been extracted and when the bolt is closed.

I desire it to be understood that the tongue 14 may be of any desired length, and I furthermore desire it to be understood that while the controlling-ring or cut-off is at all times loosely mounted on the bolt B it may be held in place in any desired manner. Usually, however, it is held in position by entering a recess 15 formed upon the exterior of the bolt B, as illustrated in Fig. 7.

When it is desired to leave a cartridge in the barrel and draw out the bolt for the purpose of charging the magazine, the controlling-ring is shifted to the position shown in Fig. 3, whereby the offset 12 is carried out from the slot or recess 10 in the extractor and engages with the left-hand side of the bolt-casing B', and the tongue 14 is carried to the right, occupying a position which will prevent it from engaging with the cartridges in the magazine. The bolt may now be drawn out, uncovering the magazine, and the extractor will remain stationary.

When the firearm is to be used as a simple repeater, the offset 12 of the controlling-ring or cut-off is carried to the right until it partially enters the groove or recess 10 in the extractor, and the tongue 14 occupies a central position below the bolt, as shown in Fig. 4. The bolt when drawn outward will now cause the extractor to operate upon the cartridge, and when the bolt is carried to its closed position the uppermost cartridge in the magazine will be forced into the breech of the barrel. When the arm is to be used as a single-loader, the magazine being held in reserve, as shown in Fig. 5, the ring is carried as far as possible toward the right or until the offset 12 shall have fully entered the recess or groove 10 in the extractor, and in this position of the ring the tongue 14 will be at the left-hand side of the magazine and will not engage with any of the cartridges in the magazine as the bolt is operated.

The improved controlling-ring or cut-off renders a firearm susceptible for use as a single-loader with the magazine held in reserve and is furthermore well adapted for such use when the magazine is empty. Furthermore, the cut-off is easily operated whether the

magazine be empty or full, and the magazine may be operated no matter how the cut-off is set. The magazine may be readily reloaded or replenished with a "clip" or with single cartridges, and single cartridges may be placed in the receiver in front of the bolt and without the assistance of the hand be pushed by the bolt into the breech-chamber whether the magazine be empty or charged and held in reserve. Furthermore, the magazine may be replenished while the barrel contains a charge without withdrawing the same.

In order that the operation of the firearm may be more fully understood, I have made illustrations, Figs. 8, 9, 10, 11, and 12, which disclose various parts of an arm to which the improvement is especially adapted, but do not restrict myself to such particular construction. The extractor E is mounted to slide in a channel 16 in the receiver B' in the customary manner. The receiver B' is constructed to accommodate the style of bolt B employed, and one form of the receiver is shown in Fig. 10, the extractor E, accompanying the receiver, being illustrated in Fig. 12.

The cartridges D are held in the magazine A in such manner that the uppermost cartridge does not interfere with the action of the bolt by means of the customary check 18 (shown in Figs. 3, 4, 5, 8, and 11) or by any other form of check. The check shown is in the nature of a block having a curved inner face adapted to engage with the shell of the uppermost cartridge D, and this block is suitably located in the receiver B', being attached thereto by a spring 17. (Shown in Figs. 8 and 10.) The rim of the uppermost cartridge engaged by the check is slightly in the path of the bolt. When the bolt is drawn out, it presses the rim down and clears itself; but when the bolt is pushed back to place the tongue 14 of the cut-off F strikes the projecting portion of the rim of the upper cartridge and carries the cartridge forward, the bullet engaging an inclined surface 19 at the bottom of the breech of the barrel. In Fig. 8 I have shown a cartridge started to the barrel, the rim of which cartridge bears upon the next lower cartridge to be held by the check, so that the rim of said next lower cartridge is entirely within the magazine.

Having thus described my invention, I claim as now and desire to secure by Letters Patent—

1. In a firearm, a bolt, and a controlling-ring or cut-off mounted to turn on the bolt, the said cut-off having means for engagement with an extractor and means for engagement with a cartridge in the magazine.
2. In a firearm, a bolt-head, a controlling-ring or cut-off mounted to turn on the bolt-head and provided with an offset adapted for engagement with an extractor, and means for turning the said controlling device so as to engage or disengage the extractor, as described.
3. A controlling-ring or cut-off for magazine firearms, consisting of a ring-body adapted

to be loosely mounted on the head of the bolt, said ring-body being provided with an exterior offset to engage or disengage the extractor of the firearm and an exterior thumb or finger piece, and a projection from the said ring-body at a point below the thumb or finger piece, as described.

4. In a magazine-firearm, the combination, with the bolt-casing, the bolt and extractor, the extractor having a groove in its inner face, a controlling-ring or cut-off mounted to turn on the bolt-head, said controlling-ring cut-off having an exterior offset adapted to enter the groove in the magazine, and a thumb finger piece together with a projection at a point below the thumb or finger piece, where the said controlling-ring or cut-off may be

turned upon the bolt-head and the offset be made to fully enter or partially enter the groove in the extractor, or be carried away ²⁰ from the said groove, and whereby also the projection from the controlling-ring or cut-off may be carried to either side of the uppermost cartridge in the magazine or be brought into position to force the cartridge from the ²⁵ magazine.

In testimony whereof I have signed my name to this specification in the presence of two subscribing witnesses.

FREDERICK HOCHBRUNN.
